UNITED STATES PATENT OFFICE.

LYMAN F. SLAVENS, OF MARSHFIELD, OREGON.

PULLEY-BLOCK.

1,209,344.

Specification of Letters Patent. Patented Dec. 19, 1916.

Application filed November 19, 1913. Serial No. 801,843.

To all whom it may concern:

Be it known that I, LYMAN F. SLAVENS, a citizen of the United States, residing at Marshfield, in the county of Coos and State 5 of Oregon, have invented certain new and useful Improvements in Pulley-Blocks; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 This invention relates to improvements in logging apparatus or appliances, more especially pulleys and "blocks" for hauling logs or other heavy objects.

The invention has for its object to provide for facilitating the handling or hauling of logs or other heavy objects.

A further object is to expedite the manipulating or connecting of the hauling cable or line to the block or yoke of the pulley.

25 A still further object is to guard against the line or cable becoming "choked" or wedged between the pulley or sheave and its carrying yoke or "block."

A still further object is to facilitate the 30 removal of the line or cable and changing the direction of the passing of the line or cable through the pulley carrying block or yoke.

A still further object is to relatively reduce the wear or abrasion upon the line or cable from the pulley block or yoke.

A still further object is to readily centralize the winding of the line or cable upon the pulley.

40 A still further object is to carry out the aforesaid ends in a simple, inexpensive, expeditious and effective manner.

The invention therefore consists of certain instrumentalities and features of construction substantially as hereinafter fully disclosed and defined by the appended claim.

In the accompanying drawings is illustrated the preferred embodiment of my invention wherein it will be understood that 50 various changes and modifications may be made as to the detailed construction and arrangement of parts without departing from the spirit of the invention, and in which drawing—

55 Figure 1 is an elevational view of the in-

vention, and Fig. 2 is a vertical sectional view thereof.

In carrying out my invention, I suitably mount a pulley or sheave 1 within a yoke or "block" 2, said pulley or sheave being 60 preferably of the structural outline or formation as disclosed, it being provided peripherally with a central annular groove or concavity 3 and with right hand and left hand similar grooves 4 and 5, respectively, 65 upon opposite sides of said central groove for the suitable reception or passing of the logging or hauling line or cable (not shown) in engagement or contact with said pulley or sheave as is well understood. By reason 70 of the arrangement of the line or cable receiving or engaging grooves of the pulley or sheave, as shown and described, it will be noted that the winding of the cable or line is centralized thereon for its continuous 75 effective action, as is apparent.

The inner terminals of the spiral grooves vanish into, or merge with the central annular groove out of alignment, and distantly separated points, whereby to guard against 80 the pulley-cable casually leaving or escaping from said central groove after having been led thereinto by said spiral grooves as would otherwise be very liable to be the case, said terminals each having its higher 85 or greater outwardly extended portion upstanding opposite the vanishing portion of the other terminal.

The spiral right-hand and left-hand grooves are flanged or guarded by flanges 90 14 terminating the pulley axially, said flanges being rounded or convex upon their inner surfaces or faces, the flanges, primarily, providing against the cable casually leaving the pulley and being deflected laterally over the threads or walls of the spiral grooves. The rounding of the surfaces or faces of the flanges tends to throw the hauling line back into the spiral grooves in event 95 of such displacement of the cable from the 100 pulley.

The yoke member or "block" 2, preferably of wrought iron, includes lateral sectional members 6 and 7, respectively, the lower or main sections thereof being adapted to form 105 bearings for the pulley or sheave shaft or axle 10, the latter being secured as usual in position therein as shown. These main or lower yoke sections are suitably connected or held together by means of a suitably 110

sleeved headed and nut-equipped bolt 11 passed through downward extensions 2^a of the member 2, the hauling line or cable passing from that end of the yoke or "block" 5 to its work. These lateral lower yoke sections are armed or reinforced upon their inner surfaces with plate-like members 12 preferably riveted to the yoke or "block," as at 13, and conforming at their lower edges 10 to the adjacent peripheral or rounded flanges 14 of the pulley, said reinforcing members 12 also serving to guard the hauling line or cable as against becoming wedged, "choked" or crowded between the 15 ends of the pulley or sheave and the yoke or "block," as is apparent from an examination of Figs. 1 and 2. The upper or minor block section includes a bail-like member 2^b having its inner or lower ends suitably bolted to 20 the lower main yoke section as at 15, said ends being received within slotted or bifurcated upper boss-like ends of terminals or the main or lower yoke sections as clearly seen in the two figures, said bail-like member 25 therefore being readily detachable or removable whereby the hauling rope, line or cable may be readily reversed in its application to or connection with the pulley or sheave simply by removing the bail-like 30 member, and whereby the necessity is avoided of pulling the line, rope or cable its whole length through the yoke or block whenever it may be desired to reverse the 35 position of the "block" or turn it "over," this being permissible simply by displacing, as above indicated, the removable bail-like member. Also in event of the breaking of any one or more parts the same may 40 be readily replaced; also the "block" may be readily adapted for use from one line to another; also the bail-like member may

be readily utilized in connection with another "block" should the yoke in use become broken or impaired. Also, this contrivance is quite light and requires but the 45 minimum labor for its transference from place to place.

Having thus fully described the several parts of my invention what I claim as new and desire to secure by Letters Patent of the 50 United States is:—

A device of the type described, including a yoke and a pulley mounted in said yoke, said pulley having a central annular peripheral groove and lateral spiral peripheral 55 grooves, the trend of said spiral grooves being in opposite directions, the inner terminals of said spiral grooves vanishing or merging into said annular peripheral groove and at out of alinement, and distantly separated points, each of said terminals accordingly having its higher or greater outwardly extended portion upstanding opposite the vanishing portion of the other terminal whereby to guard against the cable casually 60 leaving or escaping from said central groove after having been led thereinto by said spiral grooves, said pulley having flanges at the termini of its axis, with their inner surfaces or faces rounded next to said pulley 65 spiral-grooves, said yoke having its lateral members equipped to provide for guarding against the hauling line or cable becoming casually wedged between the pulley and yoke. 70

In testimony whereof I affix my signature in presence of two witnesses.

LYMAN F. SLAVENS.
